MACHINE FOR GRINDING AXLE HOUSINGS
OR THE LIKE

Robert G. Strait, Norwalk, Ohio

Application March 9, 1953, Serial No. 340,994

7 Claims. (Cl. 51—241)

1

This invention relates to a machine for grinding axle housings or the like.

A primary object of the invention is to provide a grinding machine which is adapted to be removably mounted on an axle housing or the like in centered relation thereto and which includes a grinding tool rotatable about the axis of the housing, and wherein the mounting provides for automatic movement of the grinding tool axially of the housing upon said rotation thereof about the axis of the housing.

A further object of the invention is to provide a grinding machine of the tool noted and of the same general character wherein said grinding tool is in the form of a wheel, and the same machine being characterized by a power driven shaft disposable parallel to the axis of the housing and said shaft being elongated and having cooperating means for selective attachment of a grinding wheel to either end thereof.

A still further object of the invention is to provide a grinding machine of the above noted general character which comprises improved means for mounting thereof on axle housings of different conformations and in true centered relation thereto.

Other objects and advantages of the invention will become apparent in the course of the following detailed description, taken in connection with the accompanying drawings, wherein—

Fig. 1 is a view partially in plan and partially in section and disclosing the improved grinding machine in accordance with a preferred structural embodiment thereof.

Fig. 2 is an elevational view as observed from the right side of Fig. 1.

Fig. 3 is a view corresponding to Fig. 1, but on a smaller scale and showing the application of the machine to an axle housing.

Fig. 4 is an enlarged transverse sectional view as observed in the plane of line 4—4 on Fig. 1.

Referring now in detail to the drawings, 10 designates a pivot shaft, which adjacent one end thereof is provided with a bore 11 in communication with a co-axial bore 12 of greater diameter and which latter bore opens into a relatively short bore 13 of still greater diameter and which opens through the opposite end of the shaft.

The pivot shaft 10 is adapted to be secured to the end of an axle housing H (Fig. 3) and means are provided therefor. Such means comprises a support member 14 of generally cup-form and including a base 15 and a circumferential flange 16. The base portion is provided with a central tapped opening 17 into which an externally 55 threaded reduced end portion 18 of the shaft 10 is threaded.

The base 15 of the support member is provided with a plurality of adjusting screws 19 for a purpose later to appear and the circumferential flange 16 is provided with a plurality of radially disposed adjusting screws 20, also for a purpose later to appear.

An alignment pin 21 has one end thereof disposed within the bore 11 and the major portion thereof projects from the adjacent end of shaft 10 axially thereof.

A centrally apertured circular alignment plate 22 is disposed within the support member 14 adjacent the base 15 and parallel therewith, the pin 21 extending through the aperture in the plate, and a pair of alignment cones 23 and 24 are centrally apertured for extension of the pin 21 therethrough.

20 A bracket 25 is provided and which includes a cylinder 26 in surrounding relation to the shaft 10 for rotation about the axis thereof. The cylinder 26 adjacent the outer end thereof is provided with a lock screw 27 whose inner end cooperates with the wall of a circular groove 28 in a hub 29 of a feed handle or knob 30.

One end of a feed screw 31 is secured to knob 30 as by means of a screw 32 and the feed screw cooperates with a nut 33 which is pressed into 30 the shaft bore 13 and the major portion of the feed screw operates within the shaft bore 12.

The bracket 25 further includes a pair of arms 34 which project from the cylinder 26 adjacent opposite ends and at right angles to the axis thereof.

The arms 34 are each provided with a pair of spaced apertures 35 with those in one arm axially aligned with those in the other. Furthermore, the arms 34 are each provided with a slot 36 opening through the free end thereof and bisecting the respective apertures 35.

The arms 34 are each further provided with a screw 37 extending through same intermediate their respective apertures 35, the screw being provided with a head 38 diametrically through which projects a screw manipulating pin 39.

A pair of supporting shafts 40 extend through the aligned apertures 35 and are mounted for axial adjustment through the instrumentality of the slots 36 and screws 37.

The shafts 40 in actual practice are longer than as shown in Figs. 1 and 3 and while the break in such shafts is shown intermediate the arms 34, the purpose thereof is to show the free ends 55 of the shafts.

2

The opposite ends of the shafts 40 have reduced extensions 41 extending through and suitably secured in apertures 42 in a web 43 depending from a plate 44.

A plate 45 is adjustably supported on the plate 44 in a direction transverse to the axes of shafts 40 and such adjustment is preferably effected as follows. The plate 45 is guidingly supported on the plate 44 by means of side bars 46 suitably secured to plate 45 and lapping opposite edges of the plate 44 and bars 47 secured to bars 46 lap the under side of plate 44 adjacent the opposite edges thereof.

An adjustment screw 48 has one end thereof swivelly connected to plate 44 and as at 49, and the screw is threadedly engaged within a tapped aperture in a depending flange 50 of the plate 45.

The screw 48 is provided with a manipulating handle or knob 51 by rotation of which in one or an opposite direction the plate 45 is moved toward or away from the axis of pivot shaft 10.

The adjustable plate 45 terminates in a cylinder 52 in which is supported a spindle housing 53 as by means of screws 54.

An elongated spindle 55 is rotatably supported in ball bearing assemblies 56 disposed within the housing 53 adjacent the opposite ends thereof.

A pulley 57 is secured to the spindle outwardly of one of the bearing assemblies 56 as by means of a screw 58 and a spindle cap 59 is engaged with the spindle outwardly of the other bearing assembly.

The pulley 57 and cap 59 have jointed connections 59' with opposite ends of the housing 53 for protection of the bearing assemblies.

The spindle 55 is double ended and is adapted for attachment of a grinding wheel 60 to either end thereof. For this purpose, a flange 61 is provided for each end of the spindle and a grinding wheel 60 may be locked on the spindle at either end thereof by the corresponding flange and a nut 62.

The detail construction of the machine having been described, the assembly thereof with the work to be ground and the operation thereof will now be described.

Preparatory to a grinding operation on a worn portion of an axle housing H on which a bearing is to be installed, the pivot shaft 10 is placed in vertical position with the reduced threaded end portion 18 uppermost.

The support member 14 is next threaded on to the end portion 18 with bore 11 communicating with the interior of the support member. Thereafter, the alignment plate 22 is placed within the support member. The wheel nut N is then placed on top of the alignment plate after which is placed one of the alignment cones 23 or 24 in the center of the nut, the particular cam used depending upon the size of the nut N.

After the positioning of the cone within the nut, the alignment pin 21 is centered through aligned apertures in the cam and alignment plate and into the bore 11.

The adjusting screws 20 are then turned to position their inner ends in contact with the walls of the nut after which they are firmly turned into nut locking position, the screws 19 are also drawn into firm contact with plate 22.

With the nut N thus securely positioned centrally of the support member 14, the nut is turned onto the threaded end T of the axle housing H with the pivot shaft 10 axially aligned therewith.

The remainder of this grinding machine can

then be readily assembled with the pivot shaft 10 by telescoping the cylinder 26 of the bracket 25 over the pivot shaft and then turning the feed screw 31 into nut 33 by means of the knob 30 after which the lock screw 27 is adjusted to a position with its inner end in groove 28.

It is to be understood that the grinding wheel 60 at one or the other end of the spindle 55 is power driven as by means of a motor 45a suitably mounted on plate 45 and having a belt drive connection 57a with the pulley 57 as indicated in Fig. 3.

With reference to Fig. 3 it is to be observed that the areas on the axle housing H desired to be ground are designated B-1 and B-2 or those areas in which a new bearing is to be installed.

Assuming that the area B-1 is to be ground, the knob 51 will be turned to bring the power driven grinding wheel 60 at the left end of spindle 55 into contact with the surface of said area and in the event that it is desired to position the wheel further to the right than the feed screw 31 will permit, the screws 37 may be loosened and the shafts 40 shifted in the bracket 25. This shifting may be particularly desired if the wheel 60 at the left end of the spindle is to be used to grind the inner bearing area B-2.

Furthermore, the bracket 25 and therewith the grinding wheel may be shifted axially of the shaft 10 upon loosening screw 27 and turning the knob 30 after which the screw 27 is tightened to lock the bracket 25 for rotation with the feed screw.

With the grinding wheel 60 positioned say to the right hand edge of the bearing area B-1 and set into grinding operation, the operator will grasp the bracket 25 as by means of one of the shafts 40 and swing the bracket and grinding wheel assembly circumferentially about the pivot shaft 10 in a counter-clockwise direction and with the feed screw 31 locked to the bracket by screw 27 the bracket and grinding wheel will be moved to the left simultaneously with the revolution of the rotating wheel about the area B-1.

When the grinding wheel reaches the left edge of area B-1 the bracket 25 will be rotated clockwise for travel of the grinding wheel from the left edge to the right edge of the area being ground.

Of course, it is to be understood that the knob 51 is constantly urged in a turning direction to keep the wheel 60 in firm grinding contact with the surface being ground.

To grind the area B-2 the grinding wheel 60 may be locked on the right hand end of the spindle 55 and the grinding operation carried out as above described.

Having set forth my invention in accordance with a preferred structural embodiment thereof, what I claim and desire to secure by U. S. Letters Patent is:

1. A machine for grinding cylindrical surfaces on an axle housing, comprising a pivot shaft, means on one end of the pivot shaft for rigidly securing same to the end of the axle housing, a bracket including a cylinder rotatably surrounding the pivot shaft and a pair of spaced parallel arms projecting radially therefrom, said arms having two pairs of axially aligned apertures therein adjacent their free ends, a pair of spaced shafts extending through said apertures in parallel relation to said pivot shaft, means adjustably securing the shafts in said apertures, a

plate rigidly supported by corresponding ends of the shafts, a second plate supported on said first plate for adjustment in directions at right angles to said pivot shaft, and a power driven grinding wheel assembly on said last plate.

2. The structure according to claim 1, wherein said first means comprises a cup-shaped support for receiving the nut on the end of the housing, an alignment plate within the support engageable with the outer face of the nut, adjusting screws in the rim of said cup-shaped support engageable with the side faces of the nut, and adjusting screws in the base of the support engageable with the alignment plate.

3. The structure according to claim 1, wherein said pivot shaft is provided with a bore extending axially therethrough, a feed screw disposed within said bore, a connection between said screw and said cylinder, and a nut rigidly supported within the pivot shaft having screw thread engagement with said feed screw.

4. The structure according to claim 3, wherein said connection between said screw and cylinder comprises a hand manipulatable knob rigidly secured to the outer end of the feed screw and an adjustable lock screw extending through a wall of the cylinder with its inner end disposed within a circumferential groove in said knob.

5. The structure according to claim 1, wherein said second means comprises a slot opening

10

15

20

25

through the free end of each arm and bisecting the respective apertures, and an adjustable screw extending through each arm intermediate said shafts for binding same within said apertures.

5. The structure according to claim 1 wherein said adjustment of said second plate is provided by a screw having one end thereof swivelly supported in said first plate and a flange on said second plate having a threaded aperture through which the screw extends.

6. The structure according to claim 1, wherein said grinding wheel assembly comprises an elongated housing, an elongated spindle rotatably journaled in axially spaced bearings in said housing, and means on each end of said spindle for securing a grinding wheel thereon.
